VEHICLE FENDER TRIM

John R. Bomba, Lakewood, and William F. Eberly, Aurora, Ohio, assignors to Vasco Metals Corporation, Latrobe, Pa.

Filed Oct. 16, 1968, Ser. No. 14,023

Term of patent 14 years

Int. Cl. D12—14

U.S. Cl. D14—6

FIGURE 1 is a perspective view of a vehicle fender trim embodying our new design;

FIGURE 2 is a side elevational view of the vehicle fender trim of FIGURE 1;

FIGURE 3 is a top plan view of the fender trim of FIGURE 1 as it appears before it is placed on the fender;

FIGURE 4 is a fragmentary bottom plan view of the fender trim of FIGURE 3.

The automobile shown fragmentarily and in broken lines in FIGURES 1 and 2 is included for illustrative purposes only.

We claim:

The ornamental design for a vehicle fender trim, as shown and described.
